UNITED STATES PATENT OFFICE.

ERNEST R. SEWARD, OF MADISON, WISCONSIN, ASSIGNOR TO GISHOLT MACHINE COMPANY, OF MADISON, WISCONSIN, A CORPORATION OF WISCONSIN.

TAPER ATTACHMENT FOR LATHES.

1,233,711.

Specification of Letters Patent.

Patented July 17, 1917.

Application filed October 14, 1915. Serial No. 55,911.

To all whom it may concern:

Be it known that I, ERNEST R. SEWARD, a citizen of the United States, residing at Madison, in the county of Dane and State of Wisconsin, have invented certain new and useful Improvements in Taper Attachments for Lathes, of which the following is a specification.

This invention relates to lathes, and has for its main object to provide a simple, conveniently accessible, and easily manipulated attachment for effecting uniform taper cuts of various angles on a piece held in the lathe.

The improvement constituting my present invention, its mode of use, and its advantages will all be readily understood by those skilled in the art from the following detailed description taken in connection with the accompanying drawings wherein I have illustrated one practical and preferred embodiment of the invention, and in which—

Figure 1 is a top plan view of a portion of the lathe-bed, carriage, cross slide and tool block showing my invention applied thereto; Fig. 2 is a side elevation of the parts shown in Fig. 1;

Fig. 3 is a cross section on the line 3—3 of Fig. 2;

Fig. 4 is a cross section on the line 4—4 of Fig. 2;

Fig. 5 is a detail cross section on the line 5—5 of Fig. 1.

As the general construction and organization of lathes of the type to which my present invention is adapted are well understood, I have herein illustrated in a fragmentary way only such portions of the lathe as directly coöperate with my present improvement. In the drawings 1 designates the carriage that is mounted to slide on and lengthwise of the usual ways 2 of the lathe-bed. 3 is the cross slide mounted in suitable ways on the carriage, and 4 is the tool block mounted on the carriage 3. The carriage 1 is provided with the usual depending apron 5, and is also formed with an integral extension 6 that overhangs the front side of the lathe-bed. Secured to the cross slide 3 is a non-revolving feed screw 7 which coöperates with a nut 8 keyed to the inner end of a tubular shaft 9 that is journaled in a bearing 10 of the cross slide and on its outer end carries a hand wheel 11 for

effecting manual feed of the cross slide in the manner hereinafter described.

Bolted or otherwise secured to the underside of the carriage extension 6 is a channel-shaped bracket 12 that forms a support and guide for a slide bar 13. The bracket 12 has a dovetailed groove 14 in its bottom that is engaged by a dove-tailed rack-bar 15, on the underside of the slide bar 13; such rack-bar being confined in the groove by a suitable gib 16. Pivoted on the slide bar 13 at 17 (Fig. 4) is a channel-shaped swivel bar 18, one end of which carries a clamp bolt 19 (Figs. 1 and 5), the head of which engages a transverse T-slot 20 in one end of the slide bar 13. On the slide bar adjacent to the T-slot is a scale 21 coöperating with a pointer 22 on the end of the swivel bar, whereby to determine the angle at which the swivel bar is set relatively to the line of movement of the carriage. Fitting the swivel bar 18, with capacity for relative sliding movement, is a block 23 having a round stem or stud 24 on its upper side that enters the inner end of a flat bar 25 (Fig. 4) that is slidably mounted in and crosswise of the carriage extension 26. The outer end of bar 25 is secured to a bracket piece 26 that embraces and is confined on the reduced outer end 9' of the hand feed shaft 9. A set screw 27 mounted in the forward side of the guide bracket 12 clamps the bar 25 and consequently the shaft 9 against endwise movement when it is desired to use the regular hand or power feed on the cross slide instead of the taper feed.

Referring to Fig. 3, beneath one of the ways 2 of the lathe-bed is mounted a fixed rack-bar 28 with which engages a pinion 29 on the inner end of a shaft 30, said shaft being journaled in a bushing 31 carried by said carriage apron 5. Keyed to the forward portion of shaft 30 is another pinion 32 that meshes with the rack-bar 15 carried by the slide bar 13. The forward portion of shaft 30 and the pinion 32 are housed in a depressed portion 12' of the guide bracket 12, and the forward end of the shaft extends through the latter and is provided with a knob 33 by which the shaft may be pulled forwardly sufficiently to disengage the pinion 29 from the rack-bar 28, while retaining engagement of pinion 32 with the wide rack 15.

Integral or fast with the hand feed shaft

9 is a wide pinion 34 (Fig. 4) engaged by an idler gear 35; said pinion and gear forming elements of a gear train leading from a continuously rotating shaft (not shown) in 5 the lower portion of the lathe-bed for effecting a power feed of the cross slide, when desired; such power feed being illustrated and described in my Letters Patent No. 1,168,683, dated Jan. 18, 1916, and forming no part of 10 the present invention.

Briefly describing the operation of the present improvement, when it is desired to turn a taper on a piece held in the lathe, the operator by manipulating the clamp bolt 19 15 sets the swivel bar 18 at the desired number of degrees as indicated by the scale 21. When the carriage 1 is fed by hand or power in either direction, the pinion 29 meshing with the stationary rack 28 imparts 20 a rotary motion to shaft 30 and pinion 32, which in turn moves the slide bar 13 and swivel bar 18 lengthwise with relation to the carriage 1, and the channel of the swivel-bar in which the block 23 is mounted im- 25 parts an in and out movement to block 23 which is transmitted to the cross-slide and tool block through bar 25, bracket 26, shaft 9, nut 8 and screw 7, it being understood that at such time the set-screw 27 is retracted to 30 permit free sliding movement of the bar 25.

When it is desired to turn straight work instead of tapered work, the operator pulls out the knob 33 thereby disengaging pinion 29 from rack-bar 28. He then tightens 35 up the set-screw 27 against the lower side of bar 25 which holds bracket 26 in a fixed position. He can then apply the hand feed in and out by means of the hand-wheel 11 acting through shaft 9 and nut 8 on the cross 40 feed screw 7, or he can apply the power cross feed through the gear 35 and pinion 34, as desired.

Without limiting myself to the precise details of construction herein shown and de- 45 scribed,

I claim:

1. In a taper attachment for lathes, the combination with a carriage mounted to travel on the ways of the lathe-bed and hav- 50 ing an apron, of a cross slide on said car- riage, a slide-bar guide rigid with said car- riage, a slide-bar supported by and movable lengthwise relatively to said guide, a longitudinally extending rack-bar on said slide-bar, a swivel-bar pivotally mounted on said slide-bar, means for securing said swivel-bar at any predetermined angle to the line of movement of said carriage, a block hav- 55 ing relative sliding engagement with and lengthwise of said swivel-bar, connections be- 60 tween said block and said cross slide, a fixed rack-bar on the lathe-bed, a shaft journaled in said carriage apron, a pinion on said shaft engaging said first named rack-bar, another pinion on said shaft engaging

said last named rack-bar, and manually operable means for disengaging one of said pinions from its coöperating rack-bar.

2. In a taper attachment for lathes, the combination with a carriage mounted to 70 travel on the ways of the lathe-bed, of a cross slide thereon, an endwise movable shaft having a screw-feed connection to said cross slide, a hand-wheel on the outer end of said shaft, a slide-bar guide rigid with said carriage, a slide-bar supported by and movable lengthwise relatively to said guide, a swivel-bar pivotally mounted on said slide-bar, means for securing said swivel-bar parallel with or at any predetermined angle to the 75 line of movement of said carriage, a block having relative sliding engagement with said swivel-bar, connections between said block and said endwise movable shaft, automatic means for imparting relative endwise 80 movement to said slide bar simultaneously with the travel of said carriage, and means for locking said shaft against endwise movement to permit hand-feed of said cross slide.

3. In a taper attachment for lathes, the combination with a carriage mounted to 85 travel on the ways of the lathe-bed and hav- 90 ing an apron, of a cross slide on said car- riage, an endwise movable shaft having a screw-feed connection to said cross-slide, a 95 hand wheel on the outer end of said shaft, a slide-bar guide rigid with said carriage, a slide-bar supported by and movable length- 100 wise relatively to said guide, a longitudinally extending rack-bar on said slide-bar, a swivel-bar pivotally mounted on said slide- 105 bar, means for securing said swivel-bar parallel with or at any predetermined angle to the line of movement of said carriage, a block having relative sliding engagement 110 with and lengthwise of said swivel-bar, connections between said block and said endwise movable shaft, a fixed rack-bar on the lathe- 115 bed, a shaft journaled in said carriage apron, a pinion on said shaft engaging said first named rack-bar, another pinion on said shaft 120 engaging said last-named rack-bar, manually operable means for disengaging one of said pinions from its coöperating rack-bar, and means for locking said first- 125 named shaft against endwise movement to permit hand feed of said cross slide.

4. In a taper attachment for lathes, the combination with a carriage mounted to 120 travel on the ways of the lathe-bed and hav- 125 ing an apron, of a cross slide on said car- riage, an endwise movable shaft having a screw-feed connection to said cross slide, a hand wheel on the outer end of said shaft, a slide-bar guide rigid with said carriage, a slide bar supported by and movable length- 130 wise relatively to said guide, a longitudinally extending rack-bar on said slide-bar, a swivel- bar pivotally mounted on said slide-bar, means for securing said swivel-bar at any pre-

determined angle to the line of movement of said carriage, a block having relative sliding engagement with and lengthwise of said swivel-bar, connections between said block and said endwise movable shaft, a fixed rack-bar on the lathe-bed, an endwise movable shaft journaled in said carriage-apron, a pinion on said shaft engaging said first-mentioned rack-bar, another pinion on said

shaft engaging said last-named rack-bar, 10 one of said rack-bars being sufficiently wide to remain engaged with its pinion when the other pinion has been disengaged from its coöperating rack-bar by longitudinal movement of said last-named shaft, and manually operable means for effecting such longitudinal movement of said last-named shaft. 15

ERNEST R. SEWARD.
